UNITED STATES PATENT OFFICE.

CLARENCE H. HOWARD AND HARRY M. PFLAGER, OF ST. LOUIS, MISSOURI, ASSIGNEES TO DOUBLE BODY BOLSTER COMPANY, OF ST. LOUIS, MISSOURI, A CORPORATION OF NEW JERSEY.

CAR-BOLSTER.

No. 875,818.

Specification of Letters Patent.

Patented Jan. 7, 1908.

Application filed October 23, 1907. Serial No. 398,790.

To all whom it may concern:

Be it known that we, CLARENCE H. HOWARD and HARRY M. PFLAGER, citizens of the United States, residing at St. Louis, in the 5 State of Missouri, have invented a new and useful Improvement in Car-Bolsters, of which the following is a specification:

Our invention relates particularly to that class of car double body-bolster which is composed of cast steel integral throughout, and ordinarily consists of a rectangular-shaped frame adapted to bear against the underside of the car-sills and comprising mainly, two side, and two end members, respectively arranged transversely and longitudinally to the sills, and united to each other at their ends, the side members being at a comparatively short distance apart, a middle member spanning and united at its ends to the 10 side members, and having the body center-plate on its underside adapted to engage the center-plate of the truck-bolster, and two side-bearing members united at their ends to the side members, one on each side of the middle member. By this construction, the radial movement of the truck with its wheels about the body center-plate is limited owing to the obstruction by the side members of the body-bolster to the wheels, and our invention has for its object to provide a strong, 15 rigid, and durable double body-bolster of this type in which the members are so constructed and arranged as to permit of the complete revolution of the truck with its 20 wheels and appendages about the body center-plate unobstructed by the body-bolster.

The invention consists in features of novelty as hereinafter described and claimed, reference being had to the accompanying 25 drawing forming part of this specification, whereon,

Figure 1, is a top plan view of our improved double body-bolster; Fig. 2, an end elevation thereof longitudinally with the car-sills; Fig. 3, a vertical longitudinal section through the bolster on line 3, 3, in Fig. 1, and Fig. 4, a vertical transverse section through the bolster on line 4, 4, in Fig. 1.

Like letters and numerals of reference denote like parts in all the figures.

A represents our improved car double body-bolster, which is preferably composed of cast steel integral throughout, and consists preferably, of a rectangular-shaped frame 30 having two opposite end members *a* which

are preferably L-shaped in cross section (or otherwise suitably shaped) and adapted to bear against the underside of the outer car-sills 1, longitudinally thereto, and two opposite side members *b*, preferably I-beams, 60 adapted to bear against the underside of the center and intermediate sills 2, and 3, respectively, transversely thereto, and spaced apart a sufficient distance to clear the wheels of the truck (not shown) in whatever position the latter may be radially to the body center-plate as hereinafter more particularly referred to, the end and side members *a* and *b* being united to each other at the corners of the frame in the ordinary manner. 70

Spanning and united at its ends to the side members *b*, midway between the end members *a*, is a middle longitudinal member *c* which is preferably I-shaped in cross section, having the body center-plate 4 on its underside for engaging the center-plate of the truck-bolster and perforated centrally thereat for the king-bolt (not shown). The middle member *c* extends mainly above the plane of the end and side members *a* and *b* between 75 the center sills 2, its upper part being preferably horizontal and curved downward therefrom at the ends to unite with the side members *b*, while the underside of the member *c*, between each side member *b*, and the body 80 center-plate 4 which is located below the plane of the end and side members *a* and *b*, is preferably concave longitudinally, and adapted thereto to clear the truck-wheels when moving beneath the middle member *c* during 85 a complete revolution of the truck-bolster about the body center-plate 4, the apex of each concave portion being in the present case preferably, on a level, or therewith, with the upper or bearing side of the end and 90 side members *a* and *b* as shown (or at any other desired level).

Preferably beneath, and united at two opposite parts to the middle member *c*, is preferably, a circular ring or analogous member 100 *d* which is preferably channel-shaped in cross section and concentric with the body center-plate 4, the member *d* being adapted on its underside to form a circular bearing, in lieu of the ordinary body-bolster side-bearings, 105 for engaging the side-bearings of the truck-bolster. The ring or member *d* is united to each end member *a* by two preferably channel-shaped members *d'* which are tangential to the ring *d* at opposite parts thereof, and 110

- converge therefrom to their junction at a suitable distance apart with the end member *a*, the said members *d* and *d'* being further reinforced at their junction with each other and 5 with the middle and end members *c* and *a* respectively, by suitable gussets 5, or otherwise as found most suitable, the whole forming an extended and solid bearing for engaging the side-bearings of the truck-bolster during a complete revolution thereof about the body center-plate 4, and at the same time operating as a strong and rigid brace to the frame of the bolster. Or the member *d* may be otherwise constructed to form a circular bearing on its underside for engaging the side-bearings of the truck-bolster, and otherwise braced and united to the end members *a* and middle member *c* as found desirable in practice.
- 20 In the above construction, by spacing the side members *b* wide apart and bracing the end members *a* and middle member *c*, intermediately to the side members *b*, by a suitable member having its sides converging 25 from their maximum distance apart at the middle member *c* to their junction with the end members *a*, combined with the circular bearing forming part of this bracing member, and with the arched middle member *c*, the 30 structural strength and rigidity of the body-bolster is increased and the truck with its wheels enabled to move radially about the body center-plate around sharp curves, and

if need be, through a complete revolution without obstruction by the side and other 35 members of the bolster as now occurs in the ordinary construction.

What we claim as our invention and desire to secure by Letters Patent is:—

A car-bolster of the character described, 40 consisting of two opposite end members, and two opposite side members spaced wide apart and united to the end members, the said members being adapted to bear at the top against the car-sills, a middle member spanning and uniting to the side members, and having the body center-plate on its underside, the middle member extending partly between the center sills and having its underside, between each side member and the said 45 plate, concave longitudinally, a ring or analogous member united to the middle member and adapted on its underside to form a circular bearing surface concentric with the said plate for engaging the side-bearings of the 50 truck, and suitable members uniting the said ring to the end members, substantially as described and for the purpose set forth.

In testimony whereof we have signed our names to this specification in the presence of 60 two subscribing witnesses.

CLARENCE H. HOWARD.

HARRY M. PFLAGER.

Correction in Letters Patent No. 875,818.

It is hereby certified that in Letters Patent No. 875,818, granted January 7, 1908, upon the application of Clarence H. Howard and Harry M. Pflager, of St. Louis, Missouri, for an improvement in "Car-Bolsters," an error appears in the printed specification requiring correction, as follows: In line 46, page 2, the word "uniting" should read *united*; and that the said Letters Patent should be read with this correction therein that the same may conform to the record of the case in the Patent Office.

Signed and sealed this 4th day of February, A. D., 1908.

C. C. BILLINGS,

Acting Commissioner of Patents.

- converge therefrom to their junction at a suitable distance apart with the end member *a*, the said members *d* and *d'* being further reinforced at their junction with each other and 5 with the middle and end members *c* and *a* respectively, by suitable gussets 5, or otherwise as found most suitable, the whole forming an extended and solid bearing for engaging the side-bearings of the truck-bolster during a complete revolution thereof about the body center-plate 4, and at the same time operating as a strong and rigid brace to the frame of the bolster. Or the member *d* may be otherwise constructed to form a circular bearing on its underside for engaging the side-bearings of the truck-bolster, and otherwise braced and united to the end members *a* and middle member *c* as found desirable in practice.
- 20 In the above construction, by spacing the side members *b* wide apart and bracing the end members *a* and middle member *c*, intermediately to the side members *b*, by a suitable member having its sides converging 25 from their maximum distance apart at the middle member *c* to their junction with the end members *a*, combined with the circular bearing forming part of this bracing member, and with the arched middle member *c*, the 30 structural strength and rigidity of the body-bolster is increased and the truck with its wheels enabled to move radially about the body center-plate around sharp curves, and

if need be, through a complete revolution without obstruction by the side and other 35 members of the bolster as now occurs in the ordinary construction.

What we claim as our invention and desire to secure by Letters Patent is:—

A car-bolster of the character described, 40 consisting of two opposite end members, and two opposite side members spaced wide apart and united to the end members, the said members being adapted to bear at the top against the car-sills, a middle member spanning and uniting to the side members, and having the body center-plate on its underside, the middle member extending partly between the center sills and having its underside, between each side member and the said 45 plate, concave longitudinally, a ring or analogous member united to the middle member and adapted on its underside to form a circular bearing surface concentric with the said plate for engaging the side-bearings of the 50 truck, and suitable members uniting the said ring to the end members, substantially as described and for the purpose set forth.

In testimony whereof we have signed our names to this specification in the presence of 60 two subscribing witnesses.
